ISOCHRONOUS GOVERNING MECHANISM

Arnold Maas, Berlin-Tegel, Germany, assignor
to General Electric Company, a corporation of
New York

Application April 13, 1937, Serial No. 136,696
In Germany April 21, 1936

4 Claims. (Cl. 121—42)

The present invention relates to isochronous governing mechanisms as are used, for example, to control the flow of elastic fluid to prime movers. In certain cases where a plurality of prime movers are arranged in parallel to drive electric generators connected to a line, it is customary to provide one of the prime movers with an isochronous governing mechanism to take over load fluctuation, that is, to furnish peak loads and to provide other prime movers for furnishing a base load with an ordinary governing mechanism having a rigid follow-up arrangement. At times, for instance where the prime mover furnishing the peak load fails, or where a plant including such peak load furnishing prime mover is to be connected in parallel with another plant to furnish a fixed load while such other plant is to take over load fluctuations, it becomes desirable to eliminate the isochronous characteristic of a governing mechanism, in other words, to change an isochronous governor with elastic or flexible follow-up arrangement into an ordinary governing mechanism with rigid follow-up arrangement.

The object of my invention is to provide an improved construction and arrangement of isochronous governing mechanisms which can be readily changed into ordinary governing mechanisms with rigid follow-up arrangement.

For a consideration of what I believe to be novel and my invention, attention is directed to the following description and the claims appended thereto in combination with the accompanying drawing.

The single figure of the drawing illustrates a governing mechanism embodying my invention.

The arrangement comprises an elastic fluid turbine 10 having an inlet valve 11 for controlling the flow of elastic fluid thereto. The governing mechanism for positioning the valve 11 comprises a regulating device in the present instance a speed governor 12 driven from the turbine shaft and pivotally connected to the left-hand end of a lever 13 which has an intermediate point supported on a fulcrum 14 and a right-hand end pivoted to the left-hand end of a governor lever 15. An intermediate point of the lever 15 is connected to a control member or pilot valve 16 for controlling the flow of operating fluid to and from a motor or hydraulic cylinder 17. The latter has a piston 18 with a stem 19 connected to the prime mover element to be controlled, in the present instance, the valve 11. During operation, an increase in speed due to a decrease in load causes outward movement

of the weights of the governor 12 whereby the lever 13 is turned about the fulcrum 14 in counterclockwise direction, causing upward movement of the left-hand end of lever 15 and of the pilot valve 16, resulting in the supply of operating fluid 5 to the upper side of the motor piston 18 and a discharge of operating fluid from the lower side thereof. This causes closing movement of the valve 11 and consequently reduction in flow of elastic fluid to the turbine 10, resulting in a 10 decrease in speed.

The follow-up mechanism between the motor and the pilot valve for effecting return motion of the latter upon movement of the motor piston 18 comprises a dashpot having a cylinder 20 mechanically connected to the piston 18 of the hydraulic motor and a dashpot piston 21 movably disposed within the cylinder 20. The cylinder 20 is filled with a liquid which during movement of the piston 21 is displaced between the upper side 20 and the lower side of the piston through a bypass 22. The piston 21 has a stem 23 connected to the right-hand end of the lever 15 and to a normally balanced spring 24. The connection between the piston 23 and the right-hand end of 25 the lever 15 in accordance with my invention comprises a rod 25 having portions screw-threaded in opposite directions and arranged for rotation by means of a handwheel 26. Two nuts 27 and 28 are held on the oppositely threaded 30 portions of the rod 25. The nuts are linked to a U-shaped member 29 which is secured at its lower end to the upper end of the dashpot piston stem 23. The nut 27 in addition is connected by a pivot 30 to the right-hand end of the governor lever 15. The spring 24 is held between two plates 31 which have outer portions engaging annular stops 32 and inner portions engaging abutments 33 and 34 secured to a stem or rod 35. The latter has a lower portion with a slot 36 disposed intermediate the nuts 27, 28. In the position shown, the nuts 27, 28 are forced against the lower slotted portion of the stem 35, thus establishing a mechanical connection between the spring and the dashpot piston stem 35. In this position upward movement of the dashpot piston stem 23 effects compression of the spring 24 and subsequent downward movement of the spring rod 35. Thus with the nuts 27, 28 rigidly connected to the lower end of the stem 35 the arrangement operates as an isochronous governor. Downward movement of the hydraulic motor piston 18 in response to increasing speed causes downward movement of the dashpot cylinder 20 and the piston 21 whereby the 40 45 50 55

spring 24 is compressed downwardly against the lower stops 32. Under this compression the spring effects gradual upward movement of the stem 35 and the dashpot piston 21 whereby the 5 pilot valve 16 is gradually returned to its neutral position and at the same time the length of the connection between the right-hand end of the lever 15 and the hydraulic motor piston 18 is increased due to the relative movement between 10 the dashpot piston 21 and the dashpot cylinder 20. The isochronous elements of the mechanism just described are rendered inoperative in accordance with my invention by the provision of means for rigidly connecting the dashpot cylinder 15 15 20 with the right-hand end of the lever 15 and by cutting out the spring 24. This is accomplished by providing the dashpot cylinder 20 with upwardly projecting members 37 and 38 having upper portions with slots 39, 40 through which the aforementioned screw-threaded rod 25 passes 20 freely to move up and down during isochronous operation. To change from isochronous operation to ordinary governing operation with fixed 25 return motion, the handwheel 26 is turned whereby the nuts 27, 28 are moved outward and are forced against the upper portions of the members or projections 37, 38 to establish rigid connection therewith. In this position the nuts 27, 28 and consequently also the dashpot piston 21 30 are rigidly connected to the dashpot cylinder 20, hence establishing a rigid connection between the right-hand end of the lever 15 and the hydraulic motor piston 18. With this rigid connection, upward movement of the hydraulic motor piston 18 35 causes like upward movement of the right-hand end of the lever 15 and through it return movement of the pilot valve 16.

Thus, with my invention I have accomplished an improved isochronous governing mechanism 40 which can be readily changed into an ordinary governing mechanism with fixed return motion between the governor lever and the hydraulic motor piston. To this end the dashpot piston member and the dashpot member which are connected to the governor lever and the hydraulic motor respectively may be locked together and the normally balanced spring connected to the 45 governor lever during isochronous operation may be disconnected therefrom during operation as ordinary governor with fixed return motion.

Having described the method of operation of my invention, together with the apparatus which I now consider to represent the best embodiment thereof, I desire to have it understood that the 55 apparatus shown is only illustrative and that the invention may be carried out by other means.

What I claim as new and desire to secure by Letters Patent of the United States, is:

1. Governing mechanism for prime movers 60 comprising a governor lever, a regulating device connected to the lever, a hydraulic motor, a pilot valve moved by the lever for controlling the motor and a follow-up mechanism between the pilot

valve and the motor, said follow-up mechanism including a dashpot having a cylinder member with a bypass and a piston member, one of the members being connected to the motor and the other to the lever, a normally balanced spring 5 connected to the lever, and means for disconnecting the spring and rigidly securing the piston member to the cylinder member.

2. Governing mechanism for prime movers comprising a governor lever, a regulating device 10 connected to the lever, a hydraulic motor having a piston for connection to a prime mover element to be controlled, a pilot valve connected to the lever for controlling the flow of operating fluid to the hydraulic motor, a dashpot having a cylinder 15 member and a piston member, means connecting one of the members to the hydraulic motor piston, means connecting the other member to the governor lever, a normally balanced spring and means for alternately connecting the spring to the other 20 member and for disconnecting the spring from the other member and simultaneously locking the two members together.

3. Governing mechanism for prime movers comprising a governor lever, a regulating device 25 connected to the lever, a motor having an element for connection to a prime mover element to be controlled, a control member for the motor connected to the lever, means for effecting follow-up movement of the control member upon movement of the motor element comprising a dashpot 30 having a cylinder secured to the motor element, a piston movably arranged in the cylinder and connected to the governor lever, a normally balanced spring, means for connecting the spring 35 to the piston, and means for disconnecting the spring from the piston and simultaneously locking the piston to the dashpot cylinder.

4. Governing mechanism for prime movers 40 comprising a governor lever, a speed governor to be driven from the prime mover being connected to the lever, a hydraulic motor having a piston for connection to a valve for controlling the flow of fluid to a prime mover, a pilot valve for the motor connected to the governor lever, a dashpot having 45 a cylinder connected to the hydraulic motor piston, a piston having a stem movably arranged in the dashpot, a rod with a handwheel having oppositely threaded portions, two nuts on the oppositely threaded portions of the handwheel, links connecting the nuts to the dashpot piston stem, means connecting one of the nuts to the governor lever, means including a spring rod having 50 a slotted portion intermediate the nuts whereby rotation of the screw-threaded rod in one direction effects rigid connection between the nuts and the spring rod and rotation of the screw-threaded rod in the opposite direction effects disconnection of the spring rod from the dashpot piston and rigid connection between the dashpot piston and the dashpot cylinder.

ARNOLD MAAS.
